UNITED STATES PATENT OFFICE.

HENRY ROTH, OF NEW YORK, N. Y., ASSIGNOR TO ANNIE ROTH, OF SAME PLACE.

REFLECTOR AND SIGNAL FRAME FOR CAR-LAMPS.

SPECIFICATION forming part of Letters Patent No. 278,602, dated May 29, 1883.

Application filed January 31, 1883. (No model.)

To all whom it may concern:

Be it known that I, HENRY ROTH, of the city, county, and State of New York, have invented a new and useful Improvement in Reflectors and Signal-Frames for Car-Lamps, of which the following is a full, clear, and exact description.

Reference is to be had to the accompanying drawings, forming a part of this specification, in which similar letters of reference indicate corresponding parts in all the figures.

Figure 1 is a perspective view of my improvement, part being broken away. Fig. 2 is a sectional plan view of the same. Fig. 3 is a sectional end elevation of the same, taken through the line $x-x$, Fig. 2. Fig. 4 is an elevation of one-half of the reflector. Figs. 5 and 6 represent different forms of signal-glasses.

The object of this invention is to provide reflectors and signal frames for car-lamps constructed in such a manner as to be more effective in lighting the end and platform of a car than when the said reflectors and frames are constructed in the ordinary manner.

25 The invention consists in a reflector and signal frame for car-lamps, constructed with a hinged glass-holding outer frame surrounding the outer opening and covering the inner frame. In the space between the concaved

30 ends of the main reflectors and the elongated side parts of the outer opening are placed curved and flaring reflectors to distribute light over the car-platforms. The end of the frame has an opening formed in it, in which

35 is secured the end of a tubular reflector, the other end of which is secured in an opening in the adjacent main reflector to throw light into the opposite corner of the car. The glass plates covering the openings in the frames are

40 made thick, and have the outer side of their edges beveled to cause them to refract the light more effectively, as will be hereinafter fully described.

A represents the casing or frame, which is 45 secured to the car in the usual place and in the ordinary manner. The inner side of the frame A is provided with a frame, B, hinged at its upper edge for the convenient insertion and removal of the lamp. In the frame or door B

50 is secured a large plate, C, of glass, to allow

the light from the lamp to pass freely into the car. In the outer side of the frame A is formed an oblong opening, a, which is surrounded by a metal frame, D, which is permanently secured to the front of the frame A by screws 55 or other suitable means.

To the top of the frame D is hinged a frame, E, in which is secured a plate, F, of thick glass. The glass F is beveled upon the outer side of its edges, so that the outer surface of 60 the said glass will be flush with the outer surface of the hinged frame E, or nearly so, and will thus refract more light to the platform of the car. The glass plate F is secured in place in the frame E in the ordinary manner. 65

The outer edge G of the frame E, or a flange formed around the frame E, fits around the outer edge of the inner frame D, and projects so far as to rest against the side of the frame A. The lower side of the outer frame E, when closed, is secured to the lower side of the inner frame D by a screw, H, or other suitable means. By this construction dust will be effectively prevented from entering the reflector between the frames D E. 70

To the inner edges of the frame A are secured the edges of the reflectors I, which extend in inclined directions to the outer opening in the frame A, and have their ends concaved, as shown at J in Figs. 3 and 4, to correspond 80 with the sides of the said opening. With the concaved ends of the reflectors I are connected the concaved ends of reflectors K, which are curved laterally, and are inclined outward to meet the end edges of the elongated outer 85 opening in the outer side of the frame A. With this construction the curved reflectors K and the crescent-shaped enlargements of the outer opening in the frame A cause the light to be more effectively thrown upon the platform of 90 the car, without lessening the quantity of light thrown into the car by the reflectors I.

In the inner end of the frame A is formed an opening, L, through which light is thrown into the opposite corner of the car. The opening L is surrounded by a metallic frame, D', which is secured to the frame A. The opening L is covered by a glass plate, F', which is secured in an outer metallic frame E', attached to the end of the frame A. The outer edge 95 100

G' of the frame E', or a flange formed upon the said edge, projects to fit upon the outer edge of the inner frame D' and rest against the end of the frame A, so as to effectually prevent dust from entering around the said frame E'. The glass plate F' is made thick, and has its edges beveled upon the outer side to bring the outer surface of the said glass plate flush with the outer surface of the frame E', or nearly so, to cause the light to be more effectively refracted.

To the end of the frame A, around the edge of the opening L, is secured the end of a tubular reflector, M, the other end of which is secured to the adjacent reflector I, around the edge of a corresponding opening formed through the said reflector I. With this construction the light will be more effectively distributed through the interior of the car and over the platforms than is possible with the ordinary construction.

The signal N may be a circle or a strip of colored glass secured to the frame A in any suitable manner, so as to be in the opening between the ends of the reflectors.

Having thus fully described my invention, I claim as new and desire to secure by Letters Patent—

1. The combination, with a reflector and signal frame for car-lamps, having openings in its outer side and inner end, of concaved and inclined reflectors secured to the edges of the outer opening, and a tubular reflector secured to the edge of the end opening, substantially as herein shown and described.

2. In a reflector and signal frame for car-

lamps, the combination, with the outer side of the frame A, having elongated opening, of the inner metallic frame D, and the hinged glass-holding outer frame E, having inwardly-projecting outer edge G, substantially as herein shown and described, whereby the entrance of dust around the said frame is prevented, as set forth.

3. The combination, with the frame A, provided with the outer elongated opening, a, and the inclined reflectors I, having concave ends J, of the curved reflectors K, having concaved ends, and secured to the edges of the said opening and to the concave ends of the reflectors I, substantially as herein shown and described.

4. The combination, with the frame A, provided with the end opening, L, and the inclined reflectors I, one of which is provided with an opening, of the tubular reflector M, having its ends secured, respectively, to the edges of the openings in the frame and one of the reflectors I, substantially as herein shown and described.

5. A reflector and signal frame for car-lamps, having its inner side covered by a glass plate, and provided with an inner end opening covered by a glass plate, and with reflectors for said inner side and end openings, the whole being adapted to be placed on the inside of a car, substantially as herein shown and described, whereby the whole car will be illuminated, as set forth.

HENRY ROTH.
